UNITED STATES PATENT OFFICE

AUGUST GERTH, HIDEWOOD TOWNSHIP, DEUEL COUNTY, SOUTH DAKOTA

CALCULATING MACHINE

Application filed July 11, 1931. Serial No. 550,153.

This invention relates to calculating devices whereby one number may be multiplied by another and the answer displayed on the machine and the general object of 5 the invention is to provide a relatively simple form of calculating machine which may be cheaply made, and whereby the operation of multiplying is greatly simplified.

A further object is to provide a machine 10 of this character whereby relatively large numbers may be readily multiplied by relatively large numbers without any mental effort and the answer be displayed automatically.

15 Other objects will appear in the course of the following description.

My invention is illustrated in the accompanying drawings, wherein:—

Figure 1 is a side elevation of a calculating machine constructed in accordance with 20 my invention;

Figure 2 is a vertical diametrical section through the calculating machine, the side supporting members being shown in elevation; 25

Figure 3 is a cross section on the line 3—3 of Figure 2;

Figure 4 is a front elevation broken away of the outer casing and the several cylinders;

30 Figure 5 is a diagrammatic perspective view showing the upper ends of the several cylinders and the outer casing;

Figure 6 is a fragmentary elevation of the upper portion of the outer casing;

35 Figure 7 is a fragmentary elevation of the upper portion of the middle cylinder;

Figure 8 is a fragmentary elevation of the upper portion of the outer cylinder;

40 Figure 9 is a perspective view of a combined stop and finger;

Figure 10 is an elevation of an alternative means rotating the driving shaft.

Referring to these drawings, 10 designates 45 a base of any suitable relatively heavy material having disposed on each side thereof the upstanding plates 11. Extending across these plates adjacent the base are transverse walls 12 connected to the plates 11 by tongues 13 extending through slots in the 50 plates 11.

Extending upward between the plates 11 is a shaft 14. The upper end of this shaft is supported on a cover plate 15 of an outer housing 16 constituting a supporting frame. This housing is cylindrical in form, but the 55 front of the machine is formed to provide the vertically elongated slot or opening 17. The lower end of the shaft extends through the bottom plate 18 of this housing and at the lower end the shaft is supported by a 60 bearing 19. Pinned to the lower end of the shaft 14 below the plate 18 is a crown gear 20. Extending through the member 19 which constitutes a step bearing for the 65 shaft 14 is an operating shaft 21 having a crank handle 22 and carrying a gear wheel 23 which engages the crown gear 20. Except for a reason to be now stated, beveled gears could be used in place of the gear 70 wheels 20 and 23.

Disposed below the shaft 21 is a fan carrying shaft 24 upon which a fan 25 is mounted for rotation around the shaft 24. Slidably mounted upon the shaft 24 is a pinion 26 provided with clutch teeth engageable 75 with clutch teeth 27 on the tubular shaft of the fan. These are beveled clutch teeth so that the pinion will engage with the fan only upon a rotation of the pinion 26 in one direction. The pinion 26 is provided 80 with inclined teeth 28 and the pinion is longer than the width of the gear wheel 23. Thus when the gear wheel 23 is rotated in one direction, the bearing of the teeth 28 against the teeth 27 will cause the pinion 26 to shift toward the fan and engage the teeth 27 and upon the movement of the gear wheel 23 in the opposite direction, the pinion 26 will be caused to slide away from the teeth 27 and out of engagement therewith. Thus 85 upon a rotation of the crank handle 22 in one direction, the fan will operate and upon a rotation in the other direction, the fan will not operate. This fan acts as a brake or fly wheel tending to render a rotation of the shaft 14 in one direction very steady and prevent it being rotated too rapidly.

90 While I have illustrated the shaft 21 as being provided with the crank handle 22, I do not wish to be limited to this as it 100

might be provided with a simple disk 22^a or any handle whereby the shaft 21 can be manually rotated. As before stated, the housing 16 is cylindrical in form and has an opening 17 extending longitudinally of the housing. Attached to the sides of this opening 17 are longitudinally extending metallic strips 29 formed to provide grooves 30 for the reception of a longitudinally extending strip of glass, celluloid or other transparent material 31. The lateral edges of the metallic strips 29 are formed with beads 32 and a slide 33 has sliding engagement with these beads so that the slide may be moved up or down the full length of the opening 17. This slide carries magnifying lens 34. One margin of the housing 16 projects inward beyond the corresponding strip 29 as at 35 and this margin which carries certain numerals upon it, as will be later stated, is seen through the glass 31 and through the magnifying lens 34.

Disposed within the housing 16 are three cylinders. I have illustrated three cylinders, but it is to be understood that more might be used, if desired, or that a less number might be used. The innermost cylinder is designated *a*. This is a complete cylinder and is closed at its top by the web 37 and at its bottom by the web 38.

These webs are flanged at their outer margins for attachment to the cylinder as by rivets or pins 39 and the inner margin of the lower web is flanged and engaged with a ring 40 loosely surrounding the shaft 14 and held thereto by rivets 41. The top web 37 is also flanged and engaged with a ring 40 and held to the shaft 14 by the transverse rivet or bolt 41. Thus the upper and lower ends of the innermost cylinder *a* are connected to the shaft 14 for rotation therewith.

Exteriorly of the cylinder *a* is a second cylinder *b* constructed in the same manner as the cylinder *a* and having heads at its upper and lower ends, but these heads are not connected to the shaft 14, but the cylinder is freely rotatable around the shaft. Exteriorly of the cylinder *b* there is a third cylinder *c* which is constructed in the same manner as the cylinder *b* but of greater diameter and, of course, longer as illustrated in the drawings. The cylinders *b* and *c* are each formed with a longitudinally extending slot 44 adapted when the cylinders are in their initial position to register with the slot 17.

Disposed upon the upper end of the shaft 14 is a ratchet wheel 45 and coacting with this ratchet wheel is a dog or pawl 46 mounted upon a slid able member 47 slidably mounted upon the housing 16. When this slide 47 is moved upward, it will carry the dog 46 out of engagement with the ratchet wheel. When it is moved downward, however, it will carry the dog into operative en-

gagement with the ratchet wheel and thus prevent a rotation of the ratchet wheel in the reverse direction and thus prevent the rotation of the several cylinders in the reverse direction.

When the dog 46 is raised, however, it releases the ratchet wheel 45 and permits a reverse rotation of the shaft 14 and of the several cylinders. This is accomplished by providing springs which are wound up upon a rotation of the shaft 14 in one direction, which springs act when the dog 46 is released to rotate the shaft and the several cylinders in the reverse direction. In order to secure this rotation of the shaft and cylinders, I provide a spring for each cylinder. The spring 48^c for the outermost cylinder *c* is connected at its outer end to the web 37 or upper end of the cylinder *c* and at its inner end is coiled twice around the depending flange 15^c of the cover plate 15 as at 49 and is attached to this flange so that this end of the spring is held from rotation. The spring 48^b is connected at its outer end to the outer margin of the cylinder *b* and at its inner end is coiled twice around the central depending flange of the top plate 37 for cylinder *c* as at 49 and is then attached to this depending flange.

The spring 48^a is connected at its outer end to the outer margin of the cylinder *a* and has its inner end coiled twice around the depending central flange of the top plate 37 of cylinder *b* and attached to said depending flange. The central depending flange of the cylinder *a* is, as before stated, pinned to the shaft 14. The spring 48^c is a stronger spring than the spring 48^b and the spring 48^b is stronger than the spring 48^a. Like springs 48^a, 48^b and 48^c are engaged with the lower ends of the cylinders in exactly the same manner as for the upper springs.

The several cylinders carry upon them numerals arranged in columns as will be later stated and it is necessary that when the innermost cylinder *a* has been given a full rotation, it should pick up the second cylinder *b* to cause a coincident rotation of the first and second cylinders and that when the second cylinder *b* has been given a one full rotation, it should pick up the third cylinder *c* and cause a complete rotation of this cylinder. Under these circumstances, the inner cylinder *a* will have been given three rotations, the intermediate cylinder *b* two rotations and the outermost cylinder *c* one rotation. To this end, I provide upon the inner cylinder *a* an outwardly projecting finger 50 and upon the cylinder *b* a stop 51 disposed in the path of movement of the finger 50. On the cylinder *b* there is also the outwardly projecting finger 52 engageable with a stop 53 carried by the cylinder *c* which cylinder *c* is provided with a finger 54 engageable with the stop 55 mounted

upon the casing 16. These stops and fingers may be constructed in any desired manner, but preferably as shown in Figure 9 where one of these combined stops and fingers is shown. In this figure, the combined stop and fingers consists of a small strip of metal bent upon itself to form the stop 51 and the outwardly projecting finger 52 with a supporting bracket 56. These stops and fingers are disposed, of course, both at the top and bottom of the several cylinders *a*, *b* and *c* and the top and bottom of the outer casing 16.

It will be obvious now that when the cylinders are in their neutral position, the finger of the cylinder *a* will be disposed behind the stop 51 of the cylinder *b* and the finger 52 of cylinder *b* will be disposed behind the stop 53 of cylinder *c* while the finger 54 of cylinder *c* will be disposed behind the stop 55 of the outer casing 16. Upon a complete rotation of the cylinder *a*, the finger 50 will engage the stop 51 and thus pick up the cylinder *b* to cause a simultaneous movement of the cylinders *a* and *b*. When the cylinder *b* has made a complete rotation, its finger 52 will engage the stop 53 of cylinder *c* and pick this cylinder up and carry it with it until the cylinder *c* has made a complete rotation. It will be noted that the cylinders *b* and *c* are loose upon the shaft 14 but that the cylinder *a* is fixed upon the shaft so that as the shaft is rotated by hand through the crank 22, the cylinder *a* will be given a positive rotation through one revolution, then the cylinder *b* will be picked up and given one rotation while the cylinder *a* is moving through its second rotation and that when the cylinder *a* has been rotated twice and the cylinder *b* once, then a rotation will be given to the cylinder *c*. Thus when the operation is finished, the cylinder *a* will have had three rotations, the cylinder *b* two rotations and the cylinder *c* a single rotation.

The pawl 46 will hold the shaft 14 after it has been rotated but as soon as the pawl is released, the several springs 48^a, 48^b and 48^c will cause a reverse rotation of the cylinders to their initial position.

It will be seen that after the first rotation of cylinder *a*, the spring 48^a will then have been wound three times around the hub of cylinder *b* but that a further rotation of cylinder *a* will not cause any further winding up movement of the spring 48^a because the cylinder *b* will then rotate with cylinder *a* and that upon a full rotation of the cylinder *b*, the spring 48^b will be wound up three times around the hub of cylinder *c* but there will be no further winding movement because cylinders *b* and *c* will rotate together and that one rotation of the cylinder *c* will cause the spring 48^c to be wound up three times around the hub of the cover 15

which is fixed from rotation. Therefore, all three of these springs will be under tension. Now if the parts be released, the stronger spring 48^c will act first to rotate the cylinder *c* through one rotation or until the finger 54 reaches the stop 55. Then the spring 48^b will act to rotate the cylinder *b* through one rotation or until its finger again strikes against the stop 53 on the other side thereof. Then the lighter spring 48^a will act to return the cylinder *a* to its initial position. Thus upon a release of the pawl 46, all the cylinder will be returned to their initial positions.

The innermost cylinder *a* is formed at its upper end with forty-nine circumferentially extending spaces, or in other words, the cylinder is formed with forty-nine longitudinally extending columns. The uppermost series of spaces designated generally 57 has numerals from two to fifty. Reading downward on the several vertical columns, it will be seen that the numerals show the quotients which would result from multiplying the numerals in the first column by 2, 3, 4, 5, 6, etc. Preferably, there will be 99 horizontal columns. There will, therefore, be 4,751 spaces upon the cylinder *a* showing the result of multiplying any of the numerals from 2 to 50 by any numeral from 2 to 99.

The next cylinder *b* has at its upper edge and extending circumferentially around the cylinder numerals from 51 to 100 (see Figure 7) and in series below this upper series of numerals, which upper series is designated 58, the results of multiplying any one of these numerals from 51 to 100 by any one of numerals from 2 to 99. The third or outermost cylinder *c* has upon its upper edge, the numerals from 101 to 150 (see Figure 8) designated 59 and in the several circumferential series below the results of multiplying any one of these numbers 101 to 150 by any number from 2 to 99.

As before stated, the outer cylinders *b* and *c* are each formed to provide a longitudinally extending slot 44 through which the numerals on the inner cylinder may be read. The strip 35 which projects into the field of view of the magnifying glass 34 carries upon it a vertical series of numerals from 2 to 99 or in other words, the multipliers. With this construction, if it be desired to multiply 64 by 75, the slide 33 is lowered from a position at the top of the housing to thus lower the pawl 46 into engagement with the ratchet wheel 45. The slide is pulled down until it is coincident with the first number on the strip 35. Then the crank is turned to the right so far that the figure you wish to multiply shows through the magnifying glass. In other words, the crank is turned approximately three times around. The crank is so geared that it re-

quires two turns of the crank to secure a full rotation of the first cylinder. Three turns of the crank will turn the cylinders to bring the multiplier 75 in front of the magnifying glass. The first two turns of the crank will turn the cylinder *a* around so that its finger 50 will engage the stop 51 on cylinder *b*. The third turn of the crank, therefore, will turn the cylinder *b* to such a point that the numeral 75 will be disclosed through the magnifying glass.

Then the slide is shifted downward until the numeral 64 appears upon the strip 35 and along-side of this numeral 64 will appear the quotient, namely 4,800.

Of course, obviously the cylinders may be turned until the numeral 64 appears in the magnifying glass at the beginning of the operation and then the slide shifted downward to the numeral 75 and the like quotient will appear. If the multiplicand is below 50, only two turns of the crank will be necessary to rotate the innermost cylinder once to bring any numeral from two to fifty into position in front of the magnifying glass and then the slide with the glass is shifted downward until the proper multiplier appears and the answer will be seen beside the multiplier.

It will be noted that the pawl 46 holds the cylinder or cylinders shifted after the cylinders have been properly rotated so as to leave the hand free to shift the slide vertically to show the proper multiplier. When the quotient has been secured, the slide is shifted back to its initial position which will lift the member 47, lifting the pawl 46 and the spring 48 will then cause a reverse rotation of the several cylinders to their initial position. This reverse rotation is, of course, also communicated to the shaft 14. In order to prevent too rapid rotation, I have provided the fan 25 which acts as a brake or steadier. Upon a rotation of the cylinders in the proper direction under the action of the crank 22, the fan will not be operated by reason of the separated clutch teeth 27, but when the crank is let go and the pawl 46 is lifted, the fan will be connected to the driving wheel 23 and will rotate.

The housing 16 is preferably mounted for tilting movement around the shaft 21 so that several cylinders and the housing may be tilted to bring them in the most convenient position for observation. To this end, curved slots 60 are provided concentric to the axis 21, these slots being in the members 11 and the housing is provided with outwardly projecting binding screws 61 extending through the slots and with nuts 62 whereby the housing may be held at any desired inclination within the range of the slot 60. While I have illustrated certain details which I believe to be particularly effective, I do not wish to be limited to these details

of construction, as obviously the principle of the invention may be varied in detail without departing from the spirit of the invention as defined in the appended claims.

I claim:—

1. In a calculating machine of the character described, an outer cylindrical casing having a vertical observation slot, a plurality of rotatable concentric inner cylinders, one within the other and carrying rows of numerals observable through said slot, a central manually rotatable shaft upon which the innermost cylinder is mounted for rotation therewith, a finger on each cylinder, a stop on the outer casing and on each cylinder exterior to the innermost cylinder and projecting into the path of movement of the finger on the next adjacent cylinder whereby as the inner cylinder is rotated, the several cylinders will be successively engaged and rotated, and springs one for each cylinder each connected at its outer end to its related cylinder and at its inner end coiled around the axis of the cylinders and connected to the center of the next adjacent outer cylinder, the spring connected to the innermost cylinder being weakest and the springs connected to the successive outer cylinders being successively stronger.

2. In a calculating machine of the character described, an outer cylindrical casing having a vertical observation slot, a vertically slideable element mounted for movement along said slot and having an opening, a plurality of rotatable concentric inner cylinders one within the other and carrying rows of numerals observable through the slot and said vertically slideable member, a central rotatable shaft upon which the innermost cylinder is mounted, means for causing the successive engagement of said cylinders with said shaft as it is rotated, a ratchet wheel mounted on the upper end of the shaft, a pawl mounted upon the outer casing for engagement with the ratchet wheel, the pawl being mounted upon a carrier slideable vertically on the outer casing and disposed in the path of movement of said slideable member whereby when said slideable member is raised to the full extent of the slot, the carrier will be raised to carry the pawl out of engagement with the ratchet wheel and when the slideable member is shifted downward into operative relation to the figures on the cylinders, the pawl will be lowered into operative engagement with the ratchet wheel.

In testimony whereof I hereunto affix my signature.

AUGUST GERTH. 125
